LIPSTICK CONTAINER

Anthony P. Lynn, River Grove, Ill.

Application July 19, 1949, Serial No. 105,534

4 Claims. (Cl. 206—56)

1

This invention relates to improvements in lipstick containers, and refers particularly to a lipstick container or case of the swivel type, that is, wherein the lipstick is fed outwardly for use by relative rotation of portions of the casing, the present invention being characterized in that the casing is readily refillable by the user.

The cost of the usual lipstick casing is proportionately high compared to the cost of the complete item and, hence, it would be most desirable to so construct the casing as to have it function as a permanent lipstick receptacle and to furnish cartridges of lipstick material which could be inserted by the user in the receptacle as a refill as occasion demands.

However, lipstick material, by the nature of its use, necessitates that it be relatively soft and can be easily abraded by rubbing on the lips of the user. This characteristic of the material makes handling of the lipstick material a delicate and often a "messy" task. If care is not exercised in the handling of the material the soft, brightly colored material may smear the hands or clothing of the operator or be otherwise objectionable.

Consequently, a refillable lipstick receptacle must be so constructed that the operations involving handling of the refill will be reduced to a minimum in removing the used cartridge and inserting the refill.

Accordingly, one of the important objects of my invention resides in a refillable, swivel lipstick container or receptacle so constructed that the lipstick material refill or cartridge can be conveniently inserted in the receptacle and the used cartridge removed or ejected therefrom as a simple operation involving a minimum of handling of the cartridge by the user.

Other objects and advantages of my invention will be apparent from the accompanying drawings and following detailed description.

In the drawings,

Fig. 1 is a longitudinal sectional view taken through my improved lipstick receptacle.

Fig. 2 is a bottom plan view of the device with bottom cap removed.

Fig. 3 is an elevational view parts being broken away, and parts being shown in section of the device illustrated in Figs. 1 and 2.

Fig. 4 is a transverse sectional view taken on line 4—4 of Fig. 3.

Fig. 5 is an exploded view of the device illustrating the sequence of assembly of the parts.

Fig. 6 is a longitudinal sectional view of a modification of my invention.

2

Fig. 7 is an elevational view parts being broken away, and parts being shown in section, of the device illustrated in Fig. 6.

Fig. 8 is a transverse sectional view taken on line 8—8 of Fig. 7.

Fig. 9 is a similar view illustrating the outer casing only in section.

Fig. 10 is an exploded view of the modified device.

10 Referring in detail to the drawings, and with specific reference to Figs. 1 to 5 inclusive, 1 indicates a lipstick container or casing comprising essentially an inner tubular receptacle 2, a cover 3, a base 4 and lower cap 5. The inner receptacle 15 is adapted to contain a lipstick 6 carried in a follower cup 7.

The base 4 is preferably tubular in shape and formed integral therewith and offset inwardly therefrom is a collar extension 8. Shoulder 9 20 provided by the offset juncture of the base and collar functions as a stop for the lower edge of cover 3 which telescopically engages collar 8. The cover 3 is closed at its top and functions as a closure for the receptacle 2 which carries the 25 lipstick 6.

Receptacle 2 comprises an outer sleeve 10, an inner sleeve 11 and an intermediate sleeve 12. The outer sleeve 10 is provided with a circumferential bead 13 adjacent one end thereof and in 30 assembling the device said bead rests upon the upper edge of collar 8, the end of sleeve 10 being telescopically positioned within said collar. The upper edge of the outer sleeve 10 is flanged inwardly, as shown best at 14 in Fig. 1, to present a finished appearance to receptacle 2 and prevent 35 scratching or injury to the user's lips.

The inner sleeve 11 is rigidly secured to the inner portion of base 4, being offset inwardly as at 15 (Fig. 1) to form a seat for the edge of intermediate sleeve 12. That portion of inner sleeve 11 embraced by base 4 is of double thickness and the sleeve proper as well as the inner 40 wall 16 of the embraced portion of the sleeve is provided with a longitudinal slot 17 disposed parallel to the axis of the receptacle.

Disposed between the outer sleeve 10 and inner sleeve 11 is the intermediate sleeve 12 which is constructed of relatively thin resilient metal. As has been hereinbefore described the intermediate 45 sleeve seats upon the offset portion of the inner sleeve, said latter being provided with a circumferential bead 18 adjacent its upper end against which the upper edge of the intermediate sleeve 50 abuts when the parts are assembled. In order to 55 permit the telescopic positioning of the inter-

mediate sleeve over the bead 18, said sleeve 12 is provided with a longitudinal slot 19 whereby in mounting said sleeve may be sprung sufficiently to permit clearance over the bead 18. In this manner intermediate sleeve 12 is retained in axial immovable position between the inner and outer sleeves. The outer sleeve 10 is provided with an inwardly struck finger 10' which when the parts are assembled engages in slot 19 and renders the outer sleeve 10 and intermediate sleeve 12 rotatably immovable with respect to each other. Sleeve 12 is also provided with a spiral slot 20 which opens at its lower end through the lower edge of the sleeve, the upper end of said slot being closed.

As has been hereinbefore described lipstick 6 is carried by follower cup 7 which is adapted to move axially within receptacle 2. To accomplish this axial movement, follower cup 7 carries a pin 21 which is adapted to register with slots 17 and 20 in sleeves 11 and 12 respectively. It will be noted that when pin 21 rests in slots 17 and 20, relative rotary motion of sleeve 11 with respect to sleeve 12 will cause the pin to move upwardly through both slots. The arrangement is such that outer sleeve 13 interengaged with intermediate sleeve is rotatable with respect to inner sleeve 11 and base 4. In use, base 4 and the upper portion of outer sleeve 10 are grasped by the user and the parts are rotated relative to each other to bring about the axial movement of the lipstick.

As a feature of my invention, the lower end of intermediate sleeve 12 is cut away, as shown best at 22 in Fig. 5 providing defining edges 23, 24 and 25. A struckup lug 26 is formed upon one edge defining slot 17 in inner sleeve 11. When the parts are assembled the lug 26 is disposed in the cut-away portion 22 of sleeve 12 and during rotation edge 25 rides upon the upper portion of the lug 26. In view of the fact that sleeve 12 and sleeve 11 are relatively rotatable, such relative rotation is limited in either direction by lug 26 engaging edge 23 or 24. When lug 26 engages edge 24 the open ends of slots 17 and 20 will be in register which greatly facilitates the insertion of the lipstick and follower cup in operative position within the receptacle 2.

As has been hereinbefore described, the concept of a refillable lipstick case is most desirable, but in view of the non-mechanical inclinations of the normal users of lipsticks and the fact that a lipstick, at best, is more or less messy to handle, it is necessary that the operation of inserting the refill be most simple and convenient. By the provision of the indexing stop provided by the lug 26 and edge 24 automatically aligning the ends of slots 17 and 20, the operation of inserting a refill in my casing merely involves inserting the lipstick 6 and follower cup in the lower end of the device, having pin 21 register with slot 17 in the lower end of sleeve 11 and with stop 26 in contact with edge 24, the pin is automatically insertable in slot 20. Cap 5 may then be positioned over base 4, said cap being non-rotatable with respect to said base whereby the cap and base turn together. Base 5 may carry coil spring 27 whereby cup 7 will be urged upwardly to maintain pin 21 in its proper position within both grooves 17 and 20 when it is initially inserted.

To remove the used lipstick the cup 7 is retracted in receptacle 2 until pin 21 is at the open ends of slots 17 and 20 at the time when lug 26 contacts edge 24. The end of cup 7 may then be easily secured by engaging the fingernails in the

groove 28 and cup 7 may be removed, pin 21 passing through the lower end of slot 17.

Referring particularly to Figs. 6 to 10 inclusive casing 29 indicates a modification of my invention. The casing 29 comprises essentially a tubular receptacle 30, a cover 31 and base 32. A lipstick 33 carried by a follower cup 34 is adapted to be positioned in a tubular receptacle 30 and is movable axially therein.

10 The base 32 intermediate its height is offset inwardly to provide a shoulder 35 and an upwardly extending tubular member 36 is formed integral with the base 32 and joins the base 32 at the offset shoulder 35. The offset shoulder 15 35 functions as a stop for the lower edge of the cover 31, said cover telescopically engaging the outer portion of the tubular extension 36.

The receptacle 30 comprises an outer sleeve 37, an inner sleeve 38 and an intermediate sleeve 39. The outer sleeve 37 carries a circumferential bead 40 adjacent one end thereof and that portion of the outer sleeve 37 beneath the bead 40 telescopically engages the interior surface of the tubular extension 36, bead 40 resting upon 25 the upper edge of said tubular extension.

The inner sleeve 38 terminates in an enlarged portion 41 at its lower end and is closed at its bottom as indicated best at 42 in Fig. 6. A shoulder 47 is formed between the sleeve 38 proper and the enlarged portion 41. The base 32 and the enlarged portion 41 are relatively immovable, that is when the base portion 32 is rotated sleeve 38 also rotates. Sleeve 38 is provided with an axial slot 48 which extends from its upper edge to shoulder 47.

Intermediate the outer sleeve 37 and the inner sleeve 38 the sleeve 39 is positioned. Sleeve 39 is provided for a portion of its length with a relatively straight axial slot 49. At the upper portion of the axial slot 49 said slot enters a spiral slot 50 which latter traverses a portion of the circumference of the intermediate sleeve 39. At the upper end of the slot 50, said slot connects with slot 51 which is also a portion of a helix the angle of which is reversed with respect to the angle of the helical slot 50. The slot 51 terminates closely adjacent the upper edge of the sleeve 39.

To insert the lipstick 33 and follower cup 34 into receptacle 30 the outer sleeve 37 is removed from its telescopically engaged position with respect to the tubular extension 36. The outer sleeve 37 and intermediate sleeve 39 are relatively immovable and consequently with the removal of the outer sleeve 37 the intermediate sleeve 39 is also removed. The follower cup 34 is then inserted in the upper end of the sleeve 38. A pin 52 is carried upon the outer surface of the follower cup and this pin is brought into registration with the open upper end of slot 48. The follower cup and lipstick is then moved downwardly into the inner sleeve 38, pin 52 riding in slot 48. A coil spring 53 is positioned upon the bottom 42 of the inner sleeve 38 and the bottom of cup 34 rests upon the upper portion of said spring when the lipstick 33 is inserted in the receptacle 30. The outer sleeve 37 carrying the intermediate sleeve 39 is then positioned over the inner sleeve 38 and the outer sleeve is then rotated. This rotation also rotates the intermediate sleeve 39 and when the lower end of slot 49 engages the pin 52 spring 53 moves cup 34 upwardly so that pin 52 will be positioned in slot 49 in addition to its being positioned in

slot 43. This relation of the parts is shown best in Fig. 7.

The device in this position is ready for use and it can readily be seen that by relatively rotating the outer and intermediate sleeves with respect to the inner sleeve 38 cup 34 is moved upwardly through the receptacle 39. When pin 52 carried by cup 34 reaches the juncture of slots 50 and 51 in the intermediate sleeve 39, the lipstick 33 will have pins substantially completely used. It can readily be seen that by continued relative rotation of the inner sleeve with respect to the outer and intermediate sleeves no further upward movement of the cup will take place until the relative rotation of the respective parts is reversed at which time pin 52 will travel upwardly through the reverse helical slot 51 until it approaches the upper edge of the sleeve 39. In view of the fact that pin 52 is carried adjacent bottom of cup 34 when said pin moves to the upper extremity of the reverse slot 51 said pin will simultaneously be moved to the upper end of slot 43. The upper edge of the inner sleeve 38 is relieved adjacent one side of slot 43 as shown best at 54 in Fig. 10 and consequently continued reverse relative movement of the sleeves will cause the pin 52 to ride upon the upper edge 54 of sleeve 38 and the cup 34 will be caused thereby disengaging pin 52 from the upper end of slot 51. In this manner the cup 34 carrying the used lipstick will be ejected from the receptacle 30.

I am aware that many modifications may be made in my invention and hence I do not wish to be limited except as necessitated by the prior art.

I claim as my invention:

1. A lipstick casing comprising in combination, an outer sleeve, an intermediate sleeve and an inner sleeve coaxially disposed with respect to each other, said inner sleeve being provided with a slot parallel to the axis of said sleeve opening at one end edge of said sleeve, the intermediate sleeve being provided with a helical slot opening to a corresponding end edge of said intermediate sleeve, a lipstick cup, means upon said cup for concurrent engagement in said slots, means for relatively rotating said inner and intermediate sleeves to propel said cup axially within said inner sleeve, and stop means for registering said open ends of said slots, said means comprising a lug carried upon the inner sleeve projectable into a notch provided in said intermediate sleeve and engageable with an edge of said intermediate sleeve defining said notch.

2. A lipstick casing comprising in combination, an outer tube, an intermediate sleeve and an inner sleeve coaxially disposed with respect to each other, said inner sleeve being provided with a slot parallel to the axis of said inner sleeve opening at one end edge of said sleeve, the intermediate sleeve being provided with a helical slot opening to a corresponding end edge of said intermediate sleeve, a lipstick cup, means upon said cup for concurrent movement through the open ends of said slots and engagement in said slots, means for relatively rotating said inner and intermediate sleeves to propel said cup axially within said inner sleeve, stop means upon one of said sleeves, and abutment means upon the other

sleeve engageable with said stop means when said sleeves are relatively rotated, said stop means and abutment means being disposed at a predetermined position upon said respective sleeves relative to the slots in said sleeves to register the open ends of said slots and facilitate the insertion of the cup in the inner sleeve.

3. A lipstick casing comprising in combination, an outer sleeve, a relatively immovable coaxially disposed intermediate sleeve, and an inner sleeve coaxially disposed with respect to said sleeves, said inner sleeve being provided with a slot parallel to the axis of said sleeve opening at one end edge of said sleeve, the intermediate sleeve being provided with a helical slot opening to a corresponding end edge of said intermediate sleeve, a lipstick cup, a pin upon said cup for entry into the open ends of said slots and for concurrent engagement in said slots, means for relatively rotating said inner and intermediate sleeves to propel said cup axially within said inner sleeve, stop means upon one of said slotted sleeves and abutment means upon the other of said slotted sleeves engageable with said stop means to prevent relative rotation of said slotted sleeves in one direction, said stop means and abutment means being so positioned relative to the open ends of the slots in the respective sleeves as to cause said open ends to register with each other when the stop means and abutments are in engagement to permit insertion of said cup in the inner sleeve and simultaneous initial engagement of said pin in said slots.

4. A lipstick casing comprising in combination, an outer sleeve, a relatively immovable coaxially disposed intermediate sleeve, and an inner sleeve coaxially disposed with respect to said sleeves, a base immovably connected to said inner sleeve, said inner sleeve being provided with a slot parallel to the axis of said sleeve, said base having an axial slot connecting with the slot in said inner sleeve at one end and opening at the other end to an end edge of said base, the intermediate sleeve being provided with a helical slot opening to a corresponding end edge of said intermediate sleeve, a lipstick cup, means upon said cup for concurrent engagement in said inner sleeve slot and said intermediate sleeve slot, means for relatively rotating said inner and intermediate sleeves to propel said cup axially within said inner sleeve, and stop means for registering said open ends of said slots, said means comprising a lug carried by one of said slotted sleeves projecting into a notch in said other slotted sleeve and engageable with an edge defining said notch in the notched sleeve.
